UNITED STATES PATENT OFFICE.

BERNHARD H. MILLER, OF MENDOTA, ILLINOIS.

CHIMNEY.

SPECIFICATION forming part of Letters Patent No. 717,696, dated January 6, 1903.

Application filed July 26, 1902. Serial No. 117,130. (No model.)

To all whom it may concern:

Be it known that I, BERNHARD H. MILLER, a citizen of the United States, residing at Mendota, in the county of LaSalle, State of Illinois, have invented certain new and useful Improvements in Chimneys, of which the following is a specification.

This invention relates to ventilating chimney-tops; and the object of the invention is to provide a simple, cheap, and durable top, made, preferably, of clay, in sections or parts adapted to be easily assembled in position by a bricklayer and in much less time than it would take to build the chimney to the same height with bricks.

The invention will be fully described hereinafter, reference being had to the accompanying drawings, in which—

Figure 1 is an elevation of a chimney-top embodying my invention, and Fig. 2 is a vertical section of the same.

The inner flue is indicated by A, and its lower end is designed to fit into the chimney-flue, and the brickwork of the chimney (indicated by a) will aid in maintaining the flue A in vertical position. In chimneys it is now customary to employ flue-linings of terra-cotta or similar material, such as indicated by x, and preferably the flue A will be of the same or substantially the same cross-sectional area and may thus be supported by the flue-lining.

B is a base having a central aperture to fit snugly around the flue A, and the base will be supported upon the top course of brick of the chimney and will preferably be cemented thereto.

The outer flue C surrounds the flue A to leave an air space or chamber b between them, such chamber being closed at its lower end by the base B, upon which the flue C is supported. The flue C may be cemented or otherwise secured at its lower end to the base B. The flue C is provided near its upper end with an exterior flange c, which preferably will extend entirely around it and form a support for the cap D, which fits over the outer flue C. The flue C is provided near its lower end with a plurality of narrow elongated openings e, through which air may pass into the air-chamber b. Preferably these openings will incline upwardly from the outer to the inner

side of the flue C, as clearly shown in Fig. 2. The inner flue A will extend a short distance above the outer flue C, and the cap D will expand outwardly between its upper and lower ends, and preferably the discharge-opening of the cap will be of somewhat greater area than that of the inner flue A.

The flues A and C, the base B, and cap D will preferably be made of clay, and the outer flue and the cap will preferably be vitrified on their outer surfaces.

It is intended that the flues A and C shall extend at their lower ends within the roof of the building, which latter will thus aid in supporting the outer flue in position. If desired, the outer flue may be painted and striped to imitate brick; but this is of course optional with the user. The flues may be made of different lengths and cross-sectional areas, and where two or more smoke-flues extend upside by side within a chimney the flue A may be of such size as to receive the smoke from all of them, and of course the base B, flue C, and cap D will be of sizes to correspond. In Fig. 1 the top is designed to be common to two chimney-flues.

Without limiting myself to the precise construction illustrated and described, I claim—

1. A chimney-top consisting of an inner and an outer flue with an air-chamber between them, the inner flue extending beyond the outer flue at each end and its lower end adapted to extend into and form a continuation of a chimney-flue, a base surrounding the inner flue and adapted to rest upon the top of a chimney and form a support for the outer flue, and the outer flue having air-inlet openings near its lower end and a flange near its upper end, and a cap adapted to fit over the upper end of the outer flue and be supported upon said flange, substantially as set forth.

2. The combination with a chimney having flue-linings, of a chimney-top consisting of an inner flue extending at its lower end into the chimney-flue and supported upon the flue-lining, a base supported upon the top of the chimney and having an opening through which the said inner flue extends, an outer flue surrounding said inner flue to form an air-chamber between them and supported upon the said base and terminating at its upper end in a plane below the inner flue, said outer flue

having air-inlet openings near its lower end and an exterior flange near its upper end, and a cap fitted over the upper end of the outer flue and supported upon said flange, said cap being expanded outwardly between its upper and lower ends, substantially as set forth.

5 In testimony whereof I have signed my

name to this specification in the presence of two subscribing witnesses.

BERNHARD H. MILLER.
